UNITED STATES PATENT OFFICE.

CHARLES G. JUNEAU, DECEASED, LATE OF WAUWATOSA, WISCONSIN, BY ANNA K. JUNEAU, ADMINISTRATRIX, OF WAUWATOSA, WISCONSIN, AND WALTER C. MARSHALL, OF MILWAUKEE, WISCONSIN.

REFRIGERATOR.

Application filed May 25, 1928. Serial No 280,537.

Our invention relates to a combined refrigerator and kitchen counter more especially intended for the refrigeration of fish and especially designed for use on railroad dining cars and therefore adapted to the restricted and more or less extreme conditions encountered in the kitchen portion of the cars; the refrigerator being so constructed that it may be employed as a kitchen counter.

10 Our improved refrigerator is especially designed for mechanical refrigeration obtained by mechanical units of well known construction and has for its object the provision of a construction wherein proper circulation of air will be provided without, however, permitting the entrainment of moisture from the fish holding compartments into the remainder of the refrigerator and the contamination of other food products contained in the refrigerator.

15

The objects and advantages of our invention will be more readily comprehended from the detailed description of the accompanying drawings, wherein—

20 Figure 1 is a sectional elevation of our improved refrigerator and counter, with the front wall broken away.

Figure 2 is a longitudinal sectional view taken on the line 2—2 of Figure 1 looking downwardly.

Figure 3 is a vertical sectional view taken on the line 3—3 of Figure 1 looking in the direction of the arrows.

Figure 4 is a detail sectional view taken on the line 4—4 of Figure 1, looking in the direction indicated by the arrows.

Figure 5 is a detail sectional view of one corner of a fish holding tray or container and its supporting runway.

40 The refrigerator and kitchen counter comprises an outer wall 10 which may be of suitable wood of proper thickness, or metal, having an inner spaced wall 11 which, if made of wood, is preferably covered with sheet metal. The spaces intermediate of the walls at the sides, top and bottom are filled with suitable insulating material such as cork board, indicated at 12, of suitable thickness to thoroughly insulate the refrigerator; the cork-board being preferably sealed with a non-odorant cold seal cement. The refrigerator, preferably at a central point and adjacent to the top, is provided with the mechanical refrigerating unit comprising the usual fluid hold-

ing container 13 with its fins and coils indicated at 14, secured in place in any suitable manner. As the refrigerating unit is of a well known construction detailed description and illustration thereof need not be entered into.

45 Disposed transversely of the refrigerator and extending from front wall to rear wall are a pair of spaced apart baffles or partitions 15, 15 consisting of suitable insulating material, such as cork board covered with sheet metal; the partitions or baffles being arranged in spaced relation with the top and bottom of the refrigerator so as to provide the air passages 16 and 17 above and below the partitions or baffles to permit proper circulation of air. The partitions or baffles 15, 15 on the opposite faces and at points intermediate of the top and bottom edges thereof are provided with the inwardly and downwardly sloping baffle portions 18, 18, terminating adjacent to the vertical center line of the refrigerator in spaced relation to provide an air throat or passage 19 therebetween.

50 The bottom of the refrigerator adjacent to the partitions or baffles 15 and on what may be termed the inner sides thereof are provided with suitable angle irons 20 extending transversely from front to rear of the refrigerator with the ends of the angle irons bent downwardly and secured on the bottom 21 of the refrigerator. The angle irons 20 are arranged in pairs on opposite sides of the vertical center line and therefore on opposite sides of the air passage 19. These angle irons provide suitable supports and run-ways for the fish holding trays or drawers 22 which extend from front to rear of the refrigerator. The trays are preferably of sheet metal, having bottom and side walls and open tops; with the forward ends thereof preferably provided with a suitable hand-grasp as at 23, see Figure 4, to enable the trays or containers to be slid outwardly from the refrigerator when the doors 24 (see Figures 2 and 4) have been opened. The fish containers or trays 22 along the bottoms and at the sides adjacent to the bottom are preferably provided with a number of arcuate bosses or round protrusions 25, preferably of brass in order to permit the trays or containers to readily slide on the angle irons or runways 20 and to offer a small contact area with the angle irons so as to prevent sticking of the trays to the angle irons.

or run-ways through the formation of frost. As is apparent in Figure 1 the fish containing trays or containers 22 are located entirely beneath the partition portions or baffles 18 and in order to prevent the air from circulating across the tops of these fish containers 22 (which would carry the moisture therewith), we provide the baffle members 18 with the sheet metal spring plates or resilient strips 26 which extend from front to rear of the refrigerator. The upper ends of these strips are properly secured to the baffles 18, while the lower free longitudinal edges are bowed or bent inwardly as shown in Figure 1 so as to have snug sliding relation with the sides of the fish containers 22, thereby closing off communication between the space above the fish containers and the air duct or passage 19. We also provide the partitions or baffle walls 15, beneath the baffles 18, with similar sheet metal spring plates 27, whose free lower longitudinal edges are bowed or flexed inwardly to press against the adjacent side of the fish containers and provide sliding contact. The strips 27, like strips 26, extend the full width of the refrigerator from front to rear. It is apparent that with this construction air is practically prevented from circulating around the fish containers and as a result contamination of the other food products prevented.

The partitions or walls 15 at suitable points intermediate of the tops and bottoms are shown provided with suitable angles 28 and 35 with inwardly disposed lips 29 at the bottoms to provide rests for the shelves 30. The shelves 30 are shown consisting of suitable mesh screen preferably bound in a metal frame for reinforcement and to permit the shelves to be slid in and out on the ledges 28 and 29; the opposite sides of the shelves 30 being supported by the angle strips 31, 31 secured to the side wall of the refrigerator. These shelves preferably extend from front to rear of the refrigerator, as shown in Figure 2, providing food-holding compartments made accessible by suitable doors as at 32, see Figures 2 and 3, which may be hinged as at 33 to swing toward one side. The doors, like the walls of the refrigerator, preferably consist of wood or metal and suitable insulating material or cork board as shown at 32 in Figures 2 and 3, and adapted to fit into the door-openings in the manner usual in refrigerator construction. The bottom of the refrigerator at a suitable point may be provided with the usual drain pipe shown at 34, to care for any condensation that may accumulate.

The partitions or baffles 15 are preferably arranged to provide a somewhat larger passage 16 at top than the size of passage 17 at the bottom thereof in order to induce a rapid circulation of air.

With the construction shown, the cold air from the refrigerant-holding compartment

drops or passes downwardly through the passage 19 toward the bottom of the refrigerator along the adjacent sides of the fish containers or trays 22, arranged on each side of passage 19, and beneath the bottoms thereof toward the opposite ends of the combined refrigerator and counter. As the shelves 30 are of wire mesh or suitable foraminated material, the air is permitted to rise toward the top of the refrigerator and caused to pass through the passageways 16 into the refrigerant holding compartment where it is again chilled and caused to drop down through passage 19; a constant rapid circulation of air being thus brought about. It is apparent from the construction shown in Figure 1 that the cold air merely passes about two sides of the fish containers, namely the side walls disposed toward the cold air duct 19 and the bottoms and is not permitted to pass along the side of the fish containers disposed adjacent partitions 15 because of the closure strips 26 and 27.

In practice, we prefer to provide a separate closure or door for the refrigerant-holding compartment, which may be formed in sections as disclosed in dotted lines in Figure 1 with the two side sections 35 preferably secured in place by suitable screws, while the intermediate section 36 may be hingedly secured in place to permit ordinary inspection of the refrigerating unit. The sections 35 may be readily removed with the intermediate section 36 in the event it is found necessary to remove or replace the refrigerating unit. It is evident that instead of employing a single door for each pair of food-holding compartments formed by the shelves 30, separate door sections may be employed and other minor details of construction altered without, however, departing from the spirit of our invention, which has been described in terms employed merely as terms of description and not as terms of limitation.

What we claim is:

1. A combined refrigerator and kitchen counter comprising insulated top, bottom and side walls, insulated partition walls arranged in spaced relation extending from front wall to rear wall of the refrigerator and arranged to provide air passages at top and bottom thereof, said partition walls being each provided with opposing downwardly sloping baffles extending from front to rear of the refrigerator with the inner longitudinal edges in spaced relation to provide a downwardly disposed cold air passage therebetween, slide-ways secured adjacent to the lower ends of said partition walls and having air passages therebeneath, containers slidable on said slide-ways on each side of said cold air passage and disposed beneath said baffles, resilient plates extending from front to rear secured to the opposite faces of the partition walls and to the baffles, with their free longitudinal sides in contact with the adja-

cent sides of said containers so as to prevent passage of air across the tops of said containers, and a refrigerating medium, located above said baffles and intermediate of said partition walls.

2. A refrigerator comprising insulated top, bottom and side walls, partition walls arranged in spaced relation intermediate of the end walls and extending from front to rear of the refrigerator, said partition walls being arranged to provide air passages at the top and bottom thereof, baffles extending inwardly and downwardly in opposing relation from the adjacent sides of said partition walls and spaced apart at their inner ends to provide a cold air passage therebetween, said baffles being arranged intermediate of the upper and lower ends of the partitions to provide a refrigerant holding chamber thereabove and a cooling compartment therebeneath, slide-ways arranged in pairs intermediate of the partition walls and said cold air passage, trays slideable on said slide-ways, air sealing elements secured to said partition walls and to said baffles, extending throughout the lengths of said trays and forming air sealing relation with the sides thereof, and perforate shelves arranged intermediate of said partition walls and the ends of the refrigerator.

3. A refrigerator comprising insulated top, bottom and side walls, insulated partition walls arranged in spaced relation intermediate of the ends of the refrigerator and in spaced relation therewith and extending from front to rear, the upper and lower ends of said partition walls being in spaced relation with the top and bottom of the refrigerator to provide air passages at top and bottom, the opposite faces of said partition walls being provided with opposingly disposed downwardly sloping insulated portions terminating in spaced relation at their inner ends to provide a cold air passage therebetween, said portions being arranged intermediate of the upper and lower ends of the partition walls so as to provide a refrigerating compartment thereabove and a cooling compartment therebeneath, slide-ways arranged intermediate of said cold air passage and the partition walls and in spaced relation with the bottom of the refrigerator, metallic trays extending from front to rear of the refrigerator and slideable on said slide-ways, said trays being provided with arcuate projections at the bottom and sides for engagement with said slide-ways, resilient plates extending from front to rear of the refrigerator arranged in pairs on each side of the cold passage-way, one plate of each pair depending from the inner ends of the partition portions while the other plate of each pair is secured to the partition wall,

the free ends of said resilient plates having sealing relation with the side walls of said trays to prevent circulation of air across the top of the trays, and food stuff holding compartments arranged intermediate of said partition walls and the ends of the refrigerator.

4. A combined refrigerator and kitchen counter comprising a flat top casing having insulated top, bottom and side walls, insulated partition walls composed of sheet metal arranged in spaced relation intermediate of the end walls and extending from front to rear of the refrigerator, said partition walls having air passages above and below the same, said partition walls having inwardly and downwardly sloping baffle portions of sheet metal with insulated material therebetween, said baffle portions terminating in spaced relation with each other to provide a cold air passage therebetween, said portions and partition walls being arranged to provide a refrigerant holding compartment above the baffle portions and a cooling compartment therebeneath, metallic slide-ways arranged in said cooling compartment in pairs on each side of the cold air passage and formed to permit air circulation therebeneath, metallic trays slideable on the slide-ways, resilient elements secured to the inner ends of the baffle portions and to the partition walls beneath said baffle portions and forming air sealing relation with the sides of said trays, and perforate shelves arranged one above the other intermediate of said partition walls and the adjacent end of the refrigerator.

5. A refrigerator comprising insulated top, bottom and side walls, insulated partition walls extending from front to rear of the refrigerator and in spaced relation with the top and bottom thereof, a portion of said walls extending laterally in downward sloping direction and terminating short of the opposing wall to provide a cold air passage, said partition walls being arranged to provide a refrigerant holding compartment above said laterally disposed portion and a cooling chamber beneath said laterally disposed portion, a metallic tray adapted to fit into said cooling compartment with the bottom thereof in spaced relation with the bottom of the refrigerator, resilient metallic strips extending from front to rear of the refrigerator, one of said strips being secured to the vertically disposed portion of the partition wall while the other metallic strip is secured to the inner end of the laterally disposed portion of the partition wall with the free longitudinal edges of said strips in bearing relation with the sides of said tray.
